UNITED STATES PATENT OFFICE.

RAY HYNE, OF EVANSVILLE, WISCONSIN.

SHOCK-ABSORBER.

1,189,953.

Specification of Letters Patent.

Patented July 4, 1916.

Application filed March 13, 1916. Serial No. 83,894.

To all whom it may concern:

Be it known that I, RAY HYNE, a citizen of the United States, residing at Evansville, in the county of Rock and State of Wisconsin, have invented certain new and useful Improvements in Shock-Absorbers; and I do declare the following to be a full, clear, and exact description of the invention, such as will enable others skilled in the art to 10 which it appertains to make and use the same.

My invention which relates to improvements in shock absorbers, has for its object to provide a device of this class which may 15 be simply and inexpensively manufactured and marketed, yet which when in use will be highly efficient and durable.

With this general object in view, the invention resides in certain novel features of 20 construction to be hereinafter fully described and claimed, the descriptive matter being supplemented by the accompanying drawings which constitute a part of this application, and in which—

25 Figure 1 is a side elevation partly in section showing the invention applied, and Fig. 2 is a perspective view of a part of the axle engaging clamp and the bar by which the shock absorber proper is secured to said 30 clamp.

In specifically describing the construction shown in the drawing above briefly described, similar reference characters will be placed on corresponding parts in both views 35 and reference will be herein made to the numerous elements by their respective indices. To this end, the numeral 1 designates a cylinder preferably constructed of a single length of brass tubing of proper diameter, 40 the upper and lower ends of said cylinder being closed by upper and lower caps 2 and 3 shown in the present embodiment of the invention as threaded on said cylinder. Both caps 2 and 3 are formed with central 45 external enlargements 4 for the reception of a wrench in applying or removing said caps, and in addition to these enlargements, bosses 5 are formed integrally with said caps, said bosses extending from the peripheries of 50 the latter to the aforesaid enlargements 4 as shown and being adapted for securing the cylinder to a clamp yet to be described. The enlargement 4 of the upper cap 2 co-operates with a gland 6 in forming a stuffing box 55 through which an upright rod 7 passes slid-

ably, the lower end of said rod carrying a circular plunger plate 8 preferably out of contact with the cylinder 1 and having perforations 9 through which oil or the like confined in said cylinder may pass slowly to 60 allow the rod 7 to move gradually into and out of said cylinder, it being understood that said rod is secured to the body of the vehicle, whereas the cylinder is fixed to one axle thereof. For attaching the upper end of the 65 rod 7 to the body of the vehicle, the depressed central portion 10 of a strap of metal 11 is threaded on the upper end of said rod and locked thereon by a nut 12 disposed in the depression of said strap, the 70 ends of the latter having apertures through which attaching bolts or the like 13 are passed.

Secured by a machine screw or an equivalent device 14 to the boss 5 of the upper cap 75 2, is the upper end of an upright bar 15, the lower end of said bar being bent upon itself as shown at 16, extended upwardly to a point substantially midway between the bosses 5 and being here directed outwardly as shown at 17, thence upwardly at 18, being then bent again upon itself as disclosed at 19 and terminating in the form of a C-shaped clamp member 20 having a depending ear 21. A second screw or the like 22 passes through 80 the bar 15 directly above the bend 16 and into the boss 5 of the cap 3. This manner of constructing the member 20 and securing it to the cylinder will positively prevent removal or loosening of either of the caps 2 85 and 3, as well as being a simple and inexpensive yet rigid and durable formation. As shown clearly in Fig. 1, a second C-shaped clamp member 23 co-operates with the member 20 to secure the device on the axle 90 of the vehicle, bolts 24 being provided for drawing the two members together.

When manufacturing the improved shock absorber, or after the same is applied, the cylinder 1 will be filled with oil or another suitable fluid, whereby the plunger plate 9 is retarded in its inward or outward movement, thus absorbing violent jars which would otherwise be transferred directly 100 from the wheels of the vehicle to the body thereof. The improved device will also effectively prevent the undesirable results often caused by the recoil of the vehicle springs. In short, it will be found to be not only a simple and inexpensive article, 105 110

but one which will be highly efficient and durable and will possess a number of advantageous characteristics.

I claim:

5 1. A shock absorber including an upright cylinder to contain shock absorbing means, said cylinder having upper and lower detachable caps closing its ends, an upright bar rigidly secured at its ends to said caps to prevent removal thereof, and a clamp secured to said bar for attaching the cylinder to the running gear of a vehicle.

10 2. A shock absorber including an upright cylinder to contain shock absorbing means, and an upright bar rigidly secured to the ends of said cylinder, said bar having one of its ends bent backwardly and formed into a clamp member to assist in securing the cylinder to the running gear of a vehicle.

3. A shock absorber including an upright cylinder to contain shock absorbing means, an upright bar rigidly secured to the ends of said cylinder, one end of said bar being bent upon itself and directed outwardly, said end being then again bent upon itself and further bent into substantially the form of a C to constitute a clamp member, and an additional clamp member cooperating with the aforesaid member to secure the cylinder to the running gear of a vehicle.

In testimony whereof I have hereunto set my hand in presence of two subscribing witnesses.

RAY HYNE.
